VACUUM CLEANER

Henry T. Lang, Cleveland, Ohio, assignor to Electric Vacuum Cleaner Company, Inc., Cleveland, Ohio, a corporation of New York

Application November 16, 1935, Serial No. 50,216

4 Claims. (Cl. 200—157)

The present invention relates to vacuum cleaners and particularly to hand type vacuum cleaners such as used for cleaning walls, upholstery, and the like.

5 The object of my invention is to provide a vacuum cleaner having an improved handle construction in which a switch controlling the circuit to the cleaner is closed as the handle is gripped. For a consideration of what I believe 10 to be novel and my invention, attention is directed to the following description and the claims appended thereto.

In the accompanying drawing, Fig. 1 is a perspective view of a hand type vacuum cleaner embodying my invention; Fig. 2 is a sectional side elevation of the handle showing the switch in the open position; Fig. 3 is a sectional side elevation of the handle showing the switch in the closed position; and Fig. 4 is a sectional view taken on line 4—4 of Fig. 3.

Referring to the drawing, 1 indicates the suction nozzle, 2 indicates a brush secured to the rear edge of the suction nozzle, 3 indicates the cleaner casing, 4 indicates the bag, and 5 indicates the handle of a hand type vacuum cleaner.

The handle 5 is secured to the upper side of the cleaner casing by means of a screw 6 threaded into the front end of the cleaner casing and by screws 7 threaded through bosses 8 on the handle into the rear end of the cleaner casing. Between the ends of the handle, the handle is spaced from the cleaner casing so that the handle may be gripped by the operator. On the under side of the handle is a recess 9 within which is secured 35 a switch 10 by means of a plate 12 secured to a boss 13 by a screw 14. The switch 10 is connected in series with one of the line conductors 11 which are led in through the rear end of the handle and therefore controls the operation of the cleaner. The switch 10 is provided 40 with an operating trigger 15 which is biased to the position shown in dotted lines in Fig. 2. In this position, the switch opens the circuit in one of the line conductors 11 and thereby opens 45 the circuit to the cleaner.

For operating the switch 10, I have provided a lever 16 which is pivoted in the recess 9 on a stud 17 extending between the side walls of the handle. The lever 16 is of U-shaped section as shown in Fig. 4, the sides of the lever being adjacent the inner walls of the recess 8 and the bottom of the lever closing the recess. As shown in Fig. 2, the operating trigger 15 of the switch engages the bottom of the lever 16 and normally holds the lever in the lowered posi-

tion. In this position, the end of the lever 16 engages the cleaner casing 3 so that it is not necessary to provide a separate stop for limiting the downward movement of the lever. Due to the construction of the operating trigger 15 and the switch 10, the trigger exerts less force on the lever 16 as the lever is moved from the lowered position in which the switch 10 is open to the raised position in which the switch is closed. Less force is therefore required to hold 10 the lever 16 in the raised position.

In the use of the cleaner, the operator grips the handle of the cleaner and lifts the cleaner to the place at which it is to be used. Due to the arrangement of the lever 16 on the under side 15 of the handle, the weight of the cleaner assists in moving the lever to the raised position. Also, when the cleaner is lifted, the weight of the cleaner assists in holding the lever 16 in the raised position. The gripping force required to 20 close the circuit to the cleaner is therefore decreased and, since very little gripping force is required to hold the lever 16 in the raised position, the switch is very easy to operate, and the operator is not conscious of any extra gripping 25 force required to hold the switch closed. When the handle is released by the operator, the lever 16 is moved by the trigger 15 to the lowered position, thereby opening the circuit to the cleaner.

In some cases it is desirable that the circuit to the cleaner remain closed when the handle is not gripped by the operator. For this purpose, I have provided a pin 18 which is slidable in a slot 19 in the side wall of the handle. The pin 35 is provided with a button 20 on the outside of the handle which is held against the outside of the handle by a spring washer 21 arranged between the inside of the handle and a washer 22 fixed to the pin. The spring washer 21 provides 40 sufficient friction so that the pin 18 remains in the position to which it is moved. The side wall 23 of the lever 16 which is adjacent the pin 18 is provided with a depression 24 having a slot 25 at the bottom thereof. When the lever 16 is in 45 the raised position, the end of the pin 18 may be moved into the slot 25 thereby holding the lever in the raised position and keeping the circuit to the cleaner closed. The depression 24 is slightly larger than the washer 22 so that the washer 22 slides in the depression. When the lever 16 is in the lower position, a tongue 26 prevents movement of the pin 18 to the locking position thereby preventing locking of the lever 16 50 in the lowered position. The depression 24 is 55

provided with an opening 27 which permits movement of the lever 16 without interference from the locking pin 18 when the pin is not in the locking position.

5. What I claim as new and desire to secure by Letters Patent of the United States, is,—

1. In a hand type electric tool, a handle having a recess on its under side, a lever in said recess, means for biasing the lever outward in said recess to a position from which it will be moved inward in said recess as the handle is gripped, a switch in said recess controlled by said lever, said lever being movable to a position permitting access to the switch, and means for attaching the

10 handle to the tool, the portion of the handle intermediate its ends being spaced from the tool to provide a hand grip and an end of said lever engaging the tool for limiting the outward movement thereof when the handle is attached to the 15 tool.

2. In a hand type electric tool, a handle therefor, a recess on the under side of the handle, a lever in the recess, means for biasing said lever to a position below the handle from which it will be raised as the handle is gripped, a switch controlled by said lever, a pin slidable in and having a button on the outside of the handle, the button being located in the portion of the handle which is gripped, a slot in the lever into which 25 said pin may be moved to lock the lever in the raised position, and a member on the lever arranged to engage said pin when the lever is in its lower position for preventing movement of the pin to its locking position.

3. In a hand type electric tool, a handle therefor, a recess in the under side of the handle, a lever in the recess, means for biasing said lever to a position below the handle from which it will be raised as the handle is gripped, a switch controlled by the lever, a depression in the lever having a slot at the bottom thereof, and a pin slidable in the handle and having a button on the outside of the handle, said pin having a reduced portion adapted to be moved into said slot 10 to lock the lever in the raised position and having an enlarged portion of such size that it is slidable in the depression in the lever only when the lever is in its raised position whereby movement of the pin to the locking position is prevented 15 when the lever is in its lower position.

4. In a hand type electric tool, a handle therefor, a recess on the under side of the handle, a lever in the recess, means for biasing said lever to a position below the handle from which it will be raised as the handle is gripped, a switch controlled by said lever, a slot in the side wall of the handle, a pin in said slot having a button on the outside of the handle, a spring washer on the pin inside the handle urging said button 20 against the handle, a depression in the lever having a slot at the bottom into which said pin may be moved to lock the lever in the raised position, said washer being of such size that it is slidable in said depression only when the lever is in the 25 raised position whereby movement of the pin to the locking position is prevented when the lever is in its lower position.

HENRY T. LANG.
